(57) **CLAIM**

The ornamental design for a container lid as shown and described.

DESCRIPTION

FIG. 1 is a top perspective view of a first embodiment of a container lid showing my new design;

FIG. 2 is a bottom perspective view thereof;

FIG. 3 is a top plan view thereof;

FIG. 4 is a bottom plan view thereof;

FIG. 5 is a left hand side elevational view thereof;

FIG. 6 is a right hand side elevational view thereof;

FIG. 7 is a front elevational view thereof; and

FIG. 8 is a rear elevational view thereof.

FIG. 9 is a top perspective view of a second embodiment of a container lid showing my new design on a container.

FIG. 10 is a cross-sectional view across line A-A marked in FIG. 3.

FIG. 11 is a front enlarged cross-section view of the "B" region marked in FIG. 10; and,

FIG. 12 is a rear enlarged cross-section view of the "B" region marked in FIG. 10.

FIG. 3 is illustrated to show a line of reference marked as "A". The broken line marked as "A" is for reference to the cross-sectional of FIG. 10, and forms no part of the claimed design.

FIG. 9 is illustrated to show a non-limiting example of a container on which the container lid is mounted. The broken lines in the figure show a container or portion thereof, and forms no part of the claimed design.

FIG. 10 is illustrated to show a cross section of the line of reference marked as "A" in FIG. 3. The broken line circle marked as "B" is for reference to the cross-sectionals of FIGS. 11-12, and forms no part of the claimed design.

FIGS. 11-12 are illustrated to show cross sections of the line of reference marked as "B" in FIG. 10. The broken line circles around the outside of FIGS. 11-12 mark a section of the design that is being enlarged, and therefore form no part of the claimed design.
